United States Patent Office.

JOHN AUGUSTUS LYNCH, OF BOSTON, MASSACHUSETTS.

Design No. 4,794, dated April 11, 1871.

DESIGN FOR A STEAM-ENGINE-GOVERNOR CASE.

The Schedule referred to in these Letters Patent and making part of the same.

To all persons to whom these presents may come:

Be it known that I, JOHN AUGUSTUS LYNCH, of Boston, of the county of Suffolk and State of Massachusetts, have invented a new, useful, and ornamental Design for an Engine-Governor Case, it being intended more especially for that of the well-known "Huntoon governor;" and I do hereby declare the same to be described as follows and to be represented in the accompanying drawing, of which—

Figure 1 is a side elevation, and

Figure 2 a rear end view of such case.

The main portion or body part A of the case is cylindrical, and has on one side a circular paneled projection, B.

A cylindrical head, C, provided with base and cap moldings, as shown, projects concentrically from one end of the body.

The said body rests on an oblong concave standard, D, erected on a cylindrical plinth, E, all being as exhibited in the drawing.

I claim as my invention or production—

The said described and represented ornamental design for an engine-governor case.

J. AUGUSTUS LYNCH.
